UNITED STATES PATENT OFFICE.

GEORGE DEKOFF, OF CHICAGO, ILLINOIS.

AUTOMATIC FEED TOOTHPICK HOLDER.

Application filed April 18, 1925. Serial No. 24,035.

To all whom it may concern:

Be it known that I, GEORGE DEKOFF, a citizen of Russia (who has made application for naturalization as a citizen of the United States), residing at Chicago, in the county of Cook and State of Illinois, have invented certain new and useful Improvements in Automatic Feed Toothpick Holders, of which the following is a specification.

10 This invention relates to toothpick holders or dispensers adapted for use on the table or counter, and has reference more particularly to that type of holder which is provided with means for automatically advancing the toothpicks to an opening in the container from which they are readily withdrawn by the thumb and finger.

20 The principal object of my invention is to provide an improved and sanitary holder or dispenser of the type mentioned of simple and inexpensive construction, which may be easily loaded, which will keep the toothpicks clean, and from which the toothpicks may be easily abstracted one or two at a 25 time.

In the accompanying drawings I have illustrated a simple and practical embodiment of the principle of my invention, and referring thereto—

30 Fig. 1 is a perspective front elevation of the complete article;

Fig. 2 is a vertical axial section in the plane of the line 2—2 of Fig. 5;

35 Fig. 3 is a vertical axial section at right angles to that of Fig. 2 in the plane of the line 3—3 of Fig. 5;

Fig. 4 is a top plan view;

Fig. 5 is a horizontal section in the plane of the line 5—5 of Fig. 3; and

40 Fig. 6 is a perspective view of a tool in the nature of a handle employed in retracting the follower when the holder is to be loaded.

45 Referring to the drawings, 10 designates an upright cylinder, the lower end of which is fitted into a heavy solid circular base 11; this latter preferably equipped on its under side with a felt ring pad 12 to prevent possible scratching or other marring of the table. Coaxially disposed within the cylinder 10 is a fixed shaft or post 13 formed with a reduced threaded lower end portion 14 that extends through the base 11 and receives a fastening nut 15. The shaft 13 is

also formed with an upper reduced threaded end portion 16 that extends through a countersunk central portion 17 of a removable cap or cover 18; this latter resting at its lower edge on the upper end of the cylinder 10 and preferably formed with an outwardly offset depending flange 19 overlapping the upper end of the cylinder 10. A ball nut 20 threading onto the upper end 16 of the shaft securely fastens the cover on the cylindrical body of the container.

In one side of the circular chamber of the cup 10 is a post 21 that rests on the bottom wall 10' of the cup and is attached thereto by a screw 22 passed upwardly through the base 11 and cup bottom 10'. This post 21, the cross-sectional form of which appears in Fig. 5, is formed on its lower end with a foot 23 apertured for the passage of the shaft 13 therethrough. On its upper end it is formed with an inwardly extending arm 24 likewise apertured for the passage of the shaft 13. The screw 22, of course, locks the post 21 against turning around the shaft 13. The post 21 is formed with a flat abutment face 21' (Fig. 5), against which the toothpicks are crowded by the spring-pressed follower hereinafter described. The foot 23 is formed with an inclined upper surface 23' clearly shown in Fig. 3, that constitutes a cam to elevate the advance portion of the toothpicks under the thrust of the follower. On the upper end portion 16 of the shaft 13 is a spacing washer 25 between the top surface of the arm 24 and the under side of the cover.

90 Mounted to turn around the shaft 13 by a pair of spaced hinge lugs 26 and 27 is a follower 28 of the same height as the abutment post 21. A coil spring 29 encircling the shaft 13 between the upper and lower hinge lugs 26 and 27 of the follower is anchored at one end to the back of the fixed post 21 and at its other end to the back of the follower 28, as clearly shown in Fig. 5, so that the torsion of the spring urges the follower toward the abutment face 21' of the post 21. In the top of the follower is a hole 30 adapted to be engaged by the lower end portion 31' of a suitably bent removable handle 31, by means of which latter, when the cap or cover 18 has been removed, the follower may be readily swung backwardly by the pull of the finger on the handle 31 to

permit the device to be loaded with the toothpicks. In the upper end of the post 21 is preferably formed a socket 32, into which the upper finger-engaged portion of the handle may be entered, with the remaining portion of the handle overhanging the upper end and rear side of the post 21 as indicated by dotted lines in Fig. 2. This provides a convenient holder or receptacle 10 for the follower handle within the device itself to lessen the likelihood of the handle becoming lost or mislaid and, of course forms no essential part or feature of the device.

15 In the top of the cover 18 is formed a generally sector-shaped radial delivery opening 33 of a length substantially equal to the width of the match-holding chamber; and at the forward edge of said opening the metal 20 of the cover 18 is swaged downwardly, as shown at 34, bringing the said edge substantially into the horizontal plane of the upper end of the cup-shaped body 10.

To load the holder with matches, the ball 25 nut 20 is first withdrawn and the cover 18 removed. The handle 31 is then applied to the follower and the latter retracted by a backward pull on the handle, as indicated in Fig. 5. The follower may be drawn back 30 through something more than a half circle, if desired, and still leave ample room between the back of the follower and the back of the abutment post for the subsequent disposal of the handle within the loaded holder.

35 The arcuate chamber between the front face of the follower and the abutment face 21 of the post 21 is then filled with toothpicks disposed in upright position and resting at their lower ends on the bottom of the cylindrical cup 10. The handle being retracted, the follower 28, through the thrust of its spring 29, pushes the entire body of toothpicks forwardly, and those at the advance end of the bunch ride up the cam 23', thus 40 causing their upper ends to project upwardly through the opening 33 in the cover. The downwardly swaged wall 34 at the advance edge of the opening facilitates access by the thumb or finger to the advance row of toothpicks, which may readily be withdrawn, whereupon the toothpicks directly in rear thereof are gradually advanced by the follower into the front row, until all or 45 substantially all of the toothpicks have been withdrawn.

50 From the foregoing it will be seen that my invention provides a convenient, neat and sanitary toothpick holder wherein the toothpicks are for the most part entirely protected from dust and dirt, and may be conveniently withdrawn, one or two at a time, as required for use. When employed on the counters of restaurants, cafeterias and the like, the device manifestly discourages the wasteful propensities of some pa-

trons to grab and carry off many more toothpicks than they require.

While I have herein shown and described one practical physical embodiment of the principle of my invention, it is manifest that 70 many changes may be resorted to in the details of structure and arrangement without going outside the principle of the invention or sacrificing any of the benefits and advantages thereof. Hence, I reserve all such variations and modifications as fall within the spirit and purview of the appended claims. 75

I claim:

1. In an automatic feed toothpick dispenser, the combination of a round upright cup-shaped container having a cover formed with a delivery opening between the center and periphery thereof, a central fixed shaft in said container, a fixed post formed with an abutment face underlying said opening, a fixed cam at the lower end of said abutment face, a follower formed with hinge lugs mounted on said shaft, and a torsion spring encircling said shaft and anchored at one end to said post and at its other end to 80 said follower.

2. In an automatic feed toothpick dispenser, the combination of a round upright cup-shaped container, a cover therefor formed with a central hole and a radial delivery opening, a central shaft mounted in the bottom of said container and having a threaded upper end projecting through the hole of said cover, a nut on the upper end of said shaft to lock said cover in place, a fixed post formed with an abutment face underlying said delivery opening, a fixed cam at the lower end of said abutment face, a follower formed with upper and lower hinge lugs mounted on said shaft, and a torsion spring encircling said shaft between said lugs and anchored at one end to said post and at its other end to 90 said follower. 95

3. In an automatic feed toothpick dispenser, the combination of an upright cup-shaped container having a removable cover formed with a delivery opening, a central fixed shaft in said container, a fixed member formed with an abutment face disposed between said shaft and the circumferential wall of said container and underlying said opening, a fixed cam at the lower end of said abutment face, a spring-pressed follower hinged on said shaft and formed with a hole 100 in its upper end, and a removable handle member for retracting said follower formed with a portion adapted to fit into said hole in the follower. 105

4. In an automatic feed toothpick dispenser, the combination of an upright cup-shaped container having a removable cover formed with a delivery opening, a central fixed shaft in said container, a fixed member formed with an abutment face disposed between said shaft and the circumferential 115 wall of said container and underlying said opening, a fixed cam at the lower end of said abutment face, a spring-pressed follower hinged on said shaft and formed with a hole in its upper end, and a removable handle member for retracting said follower formed with a portion adapted to fit into said hole in the follower. 120

125

wall of said container and underlying said opening, said fixed member having a socket in the upper end thereof, a fixed cam at the lower end of said abutment face, a spring 5 pressed follower hinged on said shaft and formed with a hole in its upper end, and a removable bent handle member formed with

one straight end portion adapted to fit into said hole in the follower for retracting the latter and with another straight end portion adapted, when the handle is idle, to be housed in the recess in said post. 10

GEORGE DEKOFF.
